His Attorney.

UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

CIRCUIT INTERRUPTER.

Application filed August 16, 1926. Serial No. 129,328.

- This invention relates to circuit interrupters, particularly those provided with magnetic blowouts for dissipating the arcs occurring upon the interruption of the circuit, and the principal object of the invention is to provide an improved magnetic arc blowout arrangement whereby the arc may be dissipated over a relatively long path within a limited space.
- 13 More specifically, the invention provides an improved magnetic arc blowout arranged to twist the arc in a skew, or substantially spiral, inclosed path until the arc is extinguished. The preferred arrangement is 15 such that the arc is separated and different portions of the arc are driven by a magnetic blowout coil in opposite directions along inclosed skew, or spiral, paths to interrupt the circuit. In this way the arc 20 may be dissipated by expansion and extension to a very great length in an arc blowout inclosure having relatively small overall dimensions. Moreover, the pressure resulting from the passage of the arc along the 25 closed paths materially assists in effecting the extinguishment of the arc.
- In a preferred form of the invention, the circuit interrupter is provided with an inclosure or arc chute of arc-resisting material 30 for receiving and dividing the arc from a switch of suitable form, and the arc chute inclosure has suitable barriers or dividing walls arranged to provide a plurality of skew, or substantially spiral, inclosed paths 35 for the arc about a common axis. This may be accomplished by sub-dividing the arc chute inclosure into three interconnected chambers, or compartments, located side by side with a suitable opening for receiving 40 the arc in the middle chamber. A barrier of arc-resisting material in the middle chamber serves to divide the arc into two portions, and a blowout coil or winding is inclosed within the barrier and provided 45 with suitable terminals on the opposite sides of the barrier for electrically connecting the separated portions of the arc through the winding or coil. The interconnections or openings between the adjacent chambers, 50 as well as the terminal plates of the blowout coil, are so designed and arranged that the blowout coil is energized by the current flowing in the arc, and one portion of the arc is driven by the blowout coil from the 55 middle chamber into one side chamber, while the other portion of the arc is driven into the other side chamber. The increase in pressure due to the passage of the arc into each of the closed side chambers compresses the arc stream and thereby aids in attenuating the arc. Thus, with the openings between the middle chamber and the side chambers, as well as the barrier in the middle chamber, arranged to provide a substantially spiral inclosed path for the arcs, 60 the blowout coil is so located that the magnetic flux drives each portion of the arc in opposite directions along the spiral path.
- I have illustrated in the accompanying drawing a preferred form of circuit interrupter having a magnetic arc blowout embodying my present invention. Fig. 1 is a side elevation of the interrupter with the arc chute shown partly in section in order to more clearly illustrate the various features of construction thereof; Fig. 2 is a longitudinal section of the arc blowout along the line 2-2; and Fig. 3 is a vertical section of the arc blowout along the line 3-3.
- The interrupter comprises essentially the switch 10 and the magnetic arc blowout chute 11 for receiving and dissipating the arc from the switch 10. As shown, the switch 10 is of the auxiliary break type having the 85 main switch contact 12 arranged to be held in the closed position by the latch 13, and the auxiliary or arcing switch member 14 held in engagement with the arcing contact 15 by means of the compression spring 16. The 90 arcing contact 15 extends into the arc chute 11, as indicated in the drawing, and the auxiliary arcing switch member 14 is rotatably mounted to swing in close proximity to the opposing arcing contact or terminal 17, which also is located within the magnetic 95 arc blowout inclosure 11.
- The blowout coil 18 is inclosed within the arc barriers 19 and preferably is disposed directly above the arcing terminals 15 and 17. As more clearly shown in Figs. 2 and 3, the magnetic arc chute 11 is a box-like inclosure, formed of suitable arc-resisting material, such as asbestos board or the like, and is subdivided into the arcing chambers 100 indicated as A, B and C. The blowout coil 18 and the arcing terminals 15 and 17 are located in the middle arcing chamber, which is connected with the adjacent arcing chambers by means of the restricted openings or 105 110

windows 20 and 21. The purpose of the subdivided arcing chambers and the interconnecting windows in the arc chute is to provide a skew, or substantially spiral, inclosed path of increasing area along which the arc may be driven and attenuated by the combined action of the increasing pressure and the magnetic flux of the blowout winding or coil 18, as will be more fully set forth hereinafter. The blowout coil 18 has one terminal connected to the metallic terminal plate or strip 22, which is secured upon one side of the barrier 19 with one end extending down into proximity to the arcing terminal 15 and the other end carried up and through the opening, or window, 20 into the arcing chamber B. The other terminal of the blowout coil 18 also is connected to a terminal plate or strip 23, which is secured to the other side of the barrier 19 with one end near the arcing contact 17 and the other end extending from the middle chamber A into the adjacent arcing chamber C.

For the purpose of initially driving the arc formed upon separation of the relatively movable switch members 14 and 15 into the magnetic blowout chamber, an auxiliary arc blowout coil 24, having the magnetic flux-distributing members 25 disposed on opposite sides of the switch member 14, may be provided if desired. The auxiliary blowout coil 24 is connected between the main circuit conductor L^1 and the arcing terminal 15, while the other arcing terminal 17 is connected directly to the main circuit conductor L^2 , as indicated in Fig. 1.

My improved circuit interrupter operates in the following manner: When the latch 13 is released, the main switch member 12 is operated to the open position by the biasing spring 26, and after a short initial movement engages with the auxiliary or arcing switch member 14 to operate the latter out of engagement with the arcing terminal 15. Upon the initial opening of the main switch member 12, all of the current flowing in the main circuit conductors L^1 , L^2 , passes through the auxiliary switch member 14, the arcing contact 15, and the blowout coil 24. Thus, the auxiliary magnetic blowout 24 is energized to set up a flux for blowing the arc drawn upon the disengagement of the movable switch member 14 from the arcing terminal 15 into the main magnetic arc chute 11. As the auxiliary switch member 14 swings beneath the arcing contact 17, the arc is transferred thereto and quickly rises into contact with the terminal plates 22 and 23 of blowout coil 18. This divides the arc into two portions which are interconnected through the main magnetic blowout coil 18 and energizes the latter in accordance with the current in the arc.

The flux resulting from energization of the blowout coil 18 reacts to drive the right-hand portion of the arc in a counter-clockwise direction and the left-hand portion of the arc in a clockwise direction. The right-hand arc quickly travels along the arcing terminal 15 until one end of the arc reaches the terminal knob 26 and the other end of the arc reaches the upper end of the plate 22. All the while the arc is being extended and expanded, as indicated by the dotted lines in Fig. 1, until the arc finally passes through the opening, or window, 20 into the adjacent chamber B. Thereupon, the magnetic flux of the blowout coil 18 serves to further expand and drive the arc in a substantially spiral path, as indicated by the gradually expanding dotted lines. The heating effect of the arc upon the air within the inclosed chamber B, causes the pressure within the chamber B to rapidly increase. In this way a pressure is built up which materially aids in extinguishing the arc as it is elongated in the spiral path within the chamber B. At the same time, the left-hand arc between the arcing terminal 17 and the strip 23 is driven by the flux of blowout coil 18 in a clockwise direction. This results in one end of the arc traveling along the arcing terminal 17 until it reaches the terminal knob 27, while the other end of the arc travels to the upper end of the strip 23. Further reaction of the blowout coil expands the arc through the window 21 into the arcing chamber C, where it is expanded and driven in a counter-clockwise direction about the axis of the coil in substantially the same manner as the right-hand arc is expanded in the arcing chamber B. In actually interrupting the circuit, the operation of the magnetic blowout just described occurs substantially instantaneously or at least in a very short space of time, and the separate portions of the arc are thus quickly twisted in opposite directions until the arc breaks and the circuit between the line conductors L^1 , L^2 is interrupted.

While I have described the preferred embodiment of my invention, it will be evident to those skilled in the art that various changes and modifications can be made in the apparatus shown, without departing from the spirit of the invention.

What I claim as new, and desire to secure by Letters Patent of the United States, is:

1. A circuit interrupter comprising relatively movable switch members, an inclosure of insulating material having an opening disposed to receive the arc produced upon relative movement between said switch members and having barriers arranged to provide a plurality of interconnected chambers within the inclosure forming a substantially spiral inclosed path for building up a pressure upon passage of the arc therethrough, and a winding located in an intermediate

- one of said chambers and connected to be energized responsively to the current in the arc for setting up a magnetic field to drive the arc around said path.
- 5 2. A circuit interrupter comprising relatively movable switch members, an inclosure disposed to receive the arc from said switch members having a plurality of interconnected arcing chambers providing a substantially spiral inclosed path for building up a pressure within said chambers upon passage of the arc through said path and a winding located in an intermediate one of said arcing chambers and connected to be energized in accordance with the current in the arc for setting up a magnetic flux substantially along the axis of the spiral path in the direction required to drive the arc around said path.
- 10 3. A circuit interrupter comprising relatively movable switch members, an inclosure of insulating material providing three interconnected arcing chambers disposed in substantially parallel relation and having a restricted opening in the middle one of said chambers for receiving the arc from said switch members, a barrier located in said middle chamber for separating the arc received through said opening, the interconnection between said chambers providing a substantially spiral inclosed path for each portion of the arc about a common axis, and a winding inclosed within said barrier and
- having terminal connections for completing the circuit between the separate portions of the arc, said winding being arranged to set up a magnetic flux substantially along the common axis of said special paths to drive the said portions of the arc in opposite directions therealong.
- 15 4. A circuit interrupter comprising relatively movable switch members, an inclosed arc chute divided into a plurality of substantially parallel interconnected arcing chambers and having an opening for receiving the arc from said members into an intermediate one of the chambers, a barrier in said intermediate chamber for separating the arc received through said opening, the interconnections between said chambers providing a twisting path for each portion of the arc extending from the intermediate chamber to the adjacent chamber on an opposite side thereof, a winding inclosed within said barrier, and terminals for the winding secured to opposite sides of the barrier, and each extending into the chamber on an opposite side of the intermediate chamber, whereby the winding is interconnected between the separate portions of the arc to set up a magnetic field to drive the portions of the arc along said terminals into the adjacent arcing chambers.
- 20 In witness whereof, I have hereunto set my hand this 13th day of August, 1926.
